CLAIM

The ornamental design for a cabinet for machine tool, as shown and described.

DESCRIPTION

FIG. 1 is a front right perspective view of a first embodiment of our new design for a cabinet for machine tool;
FIG. 2 is a front left perspective view thereof;
FIG. 3 is a front elevation view thereof;
FIG. 4 is a left side elevation view thereof;
FIG. 5 is a top plan view thereof;
FIG. 6 is a bottom plan view thereof;
FIG. 7 is a right side elevation view thereof;
FIG. 8 is a rear view thereof; and,
FIG. 9 is a referential view thereof which shows the door open.
Portions illustrated in dashed lines are for illustrating environment and do not form part of the claimed design.

1 Claim, 9 Drawing Sheets
